UNITED STATES PATENT OFFICE.

JOSEPH GOLDMAN, OF WOODMERE, NEW YORK.

DESIGN FOR AN APPLIQUÉ DRESS TRIMMING.

Application filed July 7, 1926. Serial No. 18,269. Term of patent 3½ years.

To all whom it may concern:

Be it known that I, JOSEPH GOLDMAN, a citizen of the United States, residing at Woodmere, in the county of Nassau and State of New York, have invented a new and original Design for Appliquéd Dress Trimming, of which the following is a specification; reference being had to the accompanying drawing, forming a part thereof.

Fig. 2 is an edge view thereof.

I claim:

The ornamental design for an appliquéd dress trimming, as shown.

In testimony whereof I affix my signature.

JOSEPH GOLDMAN.
